UNITED STATES PATENT OFFICE.

JOB HUTCHINSON, OF BROOKLYN, NEW YORK.

TWO-CYCLE INTERNAL-COMBUSTION ENGINE.

Application filed March 30, 1920. Serial No. 369,937.

To all whom it may concern:

Be it known that I, JOB HUTCHINSON, citizen of the United States, residing at Brooklyn, in the county of Kings and State 5 of New York, have invented certain new and useful Improvements in Two-Cycle Internal-Combustion Engines, of which the following is a specification.

My invention relates to internal combustion motors of the two-cycle type, and has for its principal objects the production of a motor of this type which will be lighter and less bulky than a four-cycle motor of equal power and number of impulses per 10 revolution; which will approximate the present standard form of construction of motor vehicle engines; in which a super charge of combustible mixture may be supplied to the working cylinders to raise the initial pressure in the cylinders above atmospheric pressure and thereby increase the volumetric efficiency and the mechanical equivalent of power throughout the stroke; and which will be capable of effective low 15 throttling and at the same time act as a service brake. Other objects, and the construction by which my objects are attained, will be better understood by reference to the following description and accompanying 20 drawings.

The invention consists in the novel construction, and novel combination and arrangement of parts of an internal combustion motor with its associated parts, all as hereinafter described and claimed, and illustrated in the accompanying drawings, in which:

Figure 1 is a vertical longitudinal section through a two-cylinder motor built in accordance with the invention;

Figure 2 is a vertical cross-section through one of the motor cylinders;

Figure 3 is a plan view of the motor as shown in Figure 1;

Figure 4 is a vertical cross-section through the charging pump portion of the motor shown in Figure 1;

Figure 5 is a horizontal section taken on the line 5-5 of Figure 1;

Figure 6 is a horizontal section taken on the line 6-6 of Figure 1; and

Figure 7 is a side elevation of a six-cylinder motor embodying three units as shown in Figure 1.

Referring to the drawings, 10 and 10' indicate internal combustion cylinders, two of

which are shown in Figure 1 embodied in the same casting with flanges 11 for bolting to the motor base 12, and the usual water jacket 13.

Included in this casting is a pump cylinder 14, the lower end of which opens into the crank case of the motor base.

Motor cylinders 10 and 10' also communicate with the crank case and each is provided with a power piston 15 connected by connecting rod 16 with the usual crank 17 on the crank shaft 18. These parts are of usual construction, and hence need not be described in detail. Cranks 17 are positioned 180 degrees apart, and between them is located a third crank 19 provided with a connecting rod 20 for the lower piston 21 of the pump working within pump cylinder 14.

Each motor cylinder is provided with an inlet valve 22 mounted on valve cage 23 which fits the upper aperture of the cylinder formed to receive the same, and is held to its seat by a weak spring 24. The valve cage is held in position by a cap 25 bolted to the motor casting, or in any other suitable manner. It will thus be seen that the entire valve structure may be easily removed for inspection or repairs.

26 indicates a second pump cylinder shown secured to the motor casting in alignment with the cylinder 14, and clamped between these cylinders is a partition 27 formed with charge inlet openings 28 communicating with a central valve chamber which is provided with an upper valve 29 controlling the supply of charge to pump cylinder 26, and a lower valve 30 controlling the supply of charge to the lower pump cylinder 14.

Upper pump cylinder 26 is provided with a piston 31 connected by a rod 32 with lower pump piston 21 so that said pistons may be reciprocated simultaneously in the same direction.

Pump inlet valves 29 and 30 are preferably connected together as by a sleeve 33, and are mounted upon rod 32 for frictional sliding engagement therewith. The desired degree of friction may be obtained by the packing rings 34, or in any other suitable manner.

The lower pump piston 21 is lubricated from the crank case by the splash system, and the upper pump piston 31 is lubricated by means of a duct 35 extending up through

rod 32 from piston 21, from which latter it receives oil supplied from the connecting rod 20 and passing up through ducts in the piston 21. Any other system of lubrication desired may be employed for the upper pump piston.

Partition 27 is also provided with delivery channels, channel 36 leading from the lower pump chamber to motor cylinder 10, and 10 channel 37 leading from the upper pump chamber to motor cylinder 10'. In these delivery channels are located respectively throttle valves 38, 39, which are shown of the rocker type and may be simultaneously 15 and equally moved by hand or foot controls in any known manner through levers 40 and 41, respectively.

42, 43 represent the outlet and the inlet connections of the water jacket, respectively, 20 and each motor cylinder is provided with duplicate spark plugs 44, and a plurality of exhaust ports 45 arranged in an annular series and discharging into exhaust ring 46.

The operation of the motor may now be 25 readily understood. A combustible mixture is supplied from a carburetor or any other suitable device to charge inlet channels 28, which insure a free supply of charge. Assuming that the parts are in the position 30 shown in Figures 1, 2 and 4, this charge is being admitted to pump cylinder 14 above the piston 21, which latter is beginning its downward movement. As this movement continues the charge will be drawn in until

35 pump cylinder 14 is filled with the charge and piston 21 will then start upon its upward movement. In the meantime motor cylinder 10, in which the previous charge had been fully compressed in the position 40 shown, has delivered its power to piston 15 by the explosion of said charge, and as pump piston 21 was moving down the piston of motor cylinder 10 was moving down on its power stroke. As the pump piston begins 45 its upward movement to compress the charge, valve 30 is moved by friction with rod 32 to its closed position, at the same time opening valve 29 of the upper pump cylinder 26, this closing and opening movement 50 being effected by the joint action of fluid pressure due to the pump pistons and the friction of the valve structure with rod 32.

When power piston 15 of cylinder 10 reaches the end of the work stroke and 55 covers exhaust ports 45, the compressed charge from pump cylinder 14 is admitted through inlet valve 22 and forces out the burnt gases and at the same time fills motor cylinder 10 with the fresh charge. As motor 60 piston 15 of cylinder 10 begins to rise upon the return stroke, it closes exhaust ports 45, and permits the super-compression of the charge in the motor cylinder by the advance of pump piston 21 which continues after the 65 closing of said exhaust ports. When the

super-compression of the charge within cylinder 10 is completed by pump piston reaching the end of its stroke, valve 22 will close and the further compression of the charge on the compression stroke of the motor piston will continue.

At the same time that lower pump piston 21 was charging motor cylinder 10 and effecting the super-compression of the charge, upper pump piston 31 was drawing in the 75 charge into pump cylinder 26, which upon the downward movement of the pump pistons will be compressed and supplied to motor cylinder 10' in the same manner and on the same cycle as just described in connection with motor cylinder 10.

The exact time of opening and closing of the charge inlet valves 29 and 30 of the pump may be obtained by the proper proportioning of the connection between these 85 valves, and this in combination with the angle at which the crank 19 is set to operate the pump pistons. As shown in the drawings, the pump piston is being advanced approximately 90 degrees ahead of the working piston of the motor and delivers fresh gas sufficient to displace the burnt gas during the exhaust port period, and it continues to deliver fresh gas after the exhaust ports have closed to build up pressure above atmospheric in addition to the compression due to the movement of the power piston of the motor cylinder after it has begun its compression stroke.

The pump pistons working against a discharge pressure, the latter at no time exceeds that in the working cylinder after the working piston has advanced about 40 degrees beyond the closed exhaust ports, and these pistons can therefore be of very light 100 construction, or about equal weight to the working piston. The over-all height of the pump cylinder may be reduced by increased diameter and shorter stroke, and the increased weight of the reciprocating parts 105 may be compensated by the reduced stroke so that the piston reciprocating weight will balance.

It will be observed that the valve action in this motor is always positive, as the piston rod operates the inlet valve while the pump pistons discharge through the spring valves to the working cylinders, as the springs are only sufficiently strong to overcome the weight of the valves and to assist in seating them quickly.

When the engine is in operation and the throttle valves 38 and 39 are wide open, the charge has free access to the motor cylinders, but when the throttle valves are partly closed, the flow of charge is restricted and hence the amount of charge forced into the motor cylinders during the cycle will be diminished. This diminished flow will increase the resistance of the pump, and hence 130

in low throttling the pump will act as an efficient service brake when the motor is employed on a motor vehicle.

In the operation of the motor the work 5 pistons will counterbalance each other, and it is desirable to supply a counterbalance weight 47 to balance pump piston. This will be obvious, and other details, such as supplying breather openings 48 to the upper 10 pump cylinder, will be obvious.

Inasmuch as on the two-cycle principle an explosion and impulse occurs in each cylinder for every revolution of the crank shaft, the two-cylinder type just described 15 will be equivalent to a four-cylinder four-cycle motor having a bore and stroke equal to pump piston. Any desired increase in the number of cylinders may be obtained by adding additional units, such a motor being 20 shown in Figure 7, in which three units, A, B, and C, embodying six work cylinders are shown. The common motor base or crank case 12' carried the three units, the crank shaft connections being in accordance with 25 the usual practice in multi-cylinder motors.

While I have described what I now believe to be the best embodiment of my invention, I do not wish to be limited specifically to the construction described and illustrated. Many changes and modifications 30 may be made in the details of construction and arrangement of parts without departing from the invention, and all such changes I aim to include within the scope of the 35 appended claims.

What I claim as new, and desire to secure by Letters Patent of the United States, is:—

1. In a two-cycle motor, the combination with an internal combustion cylinder having 40 exhaust ports in the wall thereof and a single diameter power piston working in said cylinder, of a charge compressing pump adjacent said cylinder proportioned and arranged to deliver a charge under pressure 45 to said cylinder, said delivery being begun while the exhaust ports are being opened, continued during the period when they are being closed, and continued after they are closed.

50 2. In a two-cycle motor, the combination with an internal combustion cylinder having exhaust ports in the wall thereof and a single diameter power piston working in said cylinder, of a charge compressing pump adjacent 55 said cylinder proportioned and arranged to compress in said cylinder at the beginning of the compression stroke of said piston a charge at greater than atmospheric pressure.

60 3. In a two-cycle motor, the combination with an internal combustion cylinder having exhaust ports in the wall thereof and a single diameter power piston working in said cylinder, of a charge compressing pump adjacent 65 said cylinder proportioned and ar-

ranged to deliver to said cylinder after the closing of the exhaust ports a supercharge of the working combustible mixture for further compression by said piston.

4. In a two-cycle motor, the combination 70 with an internal combustion cylinder having exhaust ports in the wall thereof, of a single diameter power piston working therein and controlling said exhaust ports, a charge compressing pump adjacent said cylinder proportioned and arranged to deliver to said cylinder after the closing of said exhaust ports by said piston a supercharge of the working combustible mixture for scavenging 75 and for further compression by said piston.

5. In a two-cycle motor, the combination 80 with an internal combustion cylinder having exhaust ports in the wall thereof and a single diameter power piston in said cylinder, of a charge compressing pump adjacent 85 said cylinder for supplying directly to said cylinder a predetermined amount of charge in excess of the displacement of said power piston, said charge being introduced as soon as said exhaust ports are uncovered 90 and continuously introduced until the pressure in said working cylinder equals the pressure in said pump cylinder.

6. In a two-cycle motor, the combination 95 with an internal combustion cylinder having exhaust ports in the wall thereof and a power piston in said cylinder, of auxiliary means including a pump cylinder and pump piston for supplying to said combustion cylinder a predetermined amount of charge in 100 excess of the added displacement of said power piston and clearance space, and a common crank shaft for operating said power piston and said pump piston, said pump piston being mounted at approximately 105 85° of crank motion in advance of the power piston whereby the amount of charge supplied to the combustion cylinder exceeds the added volume of the entire piston displacement and the clearance space.

7. In a two-cycle motor, the combination 110 with twin internal combustion cylinders having exhaust ports in the wall thereof, of a single diameter power piston for each cylinder arranged to be actuated alternately, a common power shaft for said pistons, a charge compressing pump adjacent 115 said cylinders and proportioned and arranged to deliver alternately to said cylinders for further compression by said pistons a predetermined 120 charge at greater than atmospheric pressure.

8. In a two-cycle motor, the combination 125 with a plurality of internal combustion cylinders having exhaust ports in the wall thereof, of a single diameter power piston for each cylinder arranged to be actuated alternately, a common power shaft for said pistons, and a charge compressing pump device having piston displacement greater than 130

the piston displacement of either of said respective cylinders and arranged to deliver alternately to said cylinders a predetermined supercharge at greater than atmospheric pressure for further compression in said cylinders.

9. In a two-cycle motor, the combination with two internal combustion cylinders having exhaust ports in the wall thereof, of a single diameter power piston for each cylinder, a common crank shaft for said pistons, a charge compressing pump having two pistons movable simultaneously in the same direction and reciprocated from said crank shaft, and valve means for controlling the delivery from said respective pump pistons to said cylinders of a super-charge at greater than atmospheric pressure for further compression in said cylinder.

10. In a two-cycle motor, the combination with an internal combustion cylinder having exhaust ports in the wall thereof and a single diameter power piston therein, of a crank shaft to which said piston is connected, and a charge compressing pump adjacent said cylinder and having a drive connection with said shaft timed to deliver a charge directly to said cylinder, said delivery being begun at a pressure above atmospheric pressure substantially before the beginning of the compression stroke of said piston and continued after the beginning of the compression stroke.

11. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for reciprocating said pistons, a partition between abutting ends of said cylinders, and an intake valve in said partition for each cylinder.

12. In a two-cycle motor, the combination with an internal combustion cylinder and a power piston therein, of a charge compressing pump comprising a cylinder connected to deliver a charge to said internal combustion cylinder, a piston within said pump cylinder, a rod for reciprocating said pump piston, and a double intake valve for said pump having packing rings in frictional engagement with said rod, the seating of one member of said double intake valve limiting the opening movement of the opposite member of said valve.

13. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for reciprocating said pistons, a partition be-

tween abutting ends of said cylinders and formed with charge inlet channels, and an intake valve for each cylinder in said partition for determining the flow from said channels.

14. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for reciprocating said pistons, a partition between abutting ends of said cylinders, and an intake valve in said partition for each cylinder having frictional engagement with said rod.

15. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for reciprocating said pistons, a partition between abutting ends of said cylinders, and in said partition intake valves connected together for simultaneous movement for closing one while the other is open.

16. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for reciprocating said pistons, a partition between abutting ends of said cylinders, and in said partition intake valves connected together for simultaneous movement for closing one while the other is open and having frictional engagement with said rod.

17. In a two-cycle motor, the combination with an internal combustion cylinder and a power piston therein, of a charge compressing pump comprising a cylinder connected to deliver a charge to said internal combustion cylinder, a piston within said pump cylinder, a rod for reciprocating said pump piston, and a double intake valve for said pump mounted upon said rod and having packing rings in frictional sliding engagement therewith whereby the movement of said rod assists in opening and closing said valve, the seating of one member of said double intake valve limiting the opening movement of the opposite member of said valve.

18. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for

reciprocating said pistons, a partition between abutting ends of said cylinders formed with charge inlet channels and with delivery channels one to each said combustion cylinder, and an intake valve for each pump cylinder in said partition for determining the flow from said charge inlet channels.

19. In a two-cycle motor, the combination with two internal combustion cylinders and a power piston for each cylinder, of a charge compressing pump comprising aligned cylinders, a piston within each cylinder, a rod connecting said cylinders for simultaneous movement in the same direction, means for reciprocating said pistons, a removable partition between abutting ends of said cylinders formed with charge inlet channels and with delivery channels one to each of said combustion cylinders, and an intake valve for each pump cylinder in said partition for determining the flow from said charge inlet channels.

20. In a two-cycle motor, the combustion with two internal combustion cylinders, of a power piston for each cylinder, a common crank shaft for said pistons, a charge compressing pump having two pistons, a rod connecting said pump pistons for movement simultaneously in the same direction and having an oil duct longitudinally therethrough, and a connecting rod for one pump piston having a crank connection with said shaft, and means extending the length of said connecting rod and arranged to supply oil to said duct for delivery to the other pump piston.

21. In a two-cycle motor, the combination with two internal combustion cylinders and a power piston for each cylinder, of a charge compressing pump located between said cylinders and comprising aligned cylinders, means for reciprocating said pump pistons simultaneously in the same direction, means for reciprocating said pump pistons, a partition between abutting ends of said pump cylinders formed with a delivery channel therein providing a passageway from each pump cylinder to the respective combustion cylinders, and a throttle valve controlling the pressure in the pump cylinder and the delivery of charge from each channel to its combustion cylinder.

22. In a two-cycle motor, the combination with two internal combustion cylinders and a power piston for each cylinder, of a charge compressing pump located between said cylinders and comprising aligned cylinders, means for reciprocating said pump pistons simultaneously in the same direction, a removable partition between the abutting ends of said pump cylinders formed with a deliv-

ery channel therein providing a passageway from each pump cylinder to the respective combustion cylinders, and a throttle valve controlling the pressure in the pump cylinder and the delivery of charge from each channel to its combustion cylinder.

23. In a two-cycle motor, the combination with two internal combustion cylinders having exhaust ports in the wall thereof, of a power piston for each cylinder, a common crank shaft for said pistons, a charge compressing pump having two pistons movable simultaneously in the same direction and reciprocated from said crank shaft, and valve means for controlling the delivery from said respective pump pistons to said cylinders, said pump pistons being mounted at approximately 85° of crank motion in advance of the power piston whereby the amount of charge supplied to the combustion cylinder exceeds the added volume of the entire piston displacement and the clearance space and is subjected to further compression in the combustion cylinder.

24. In a two-cycle motor, the combination with an internal combustion cylinder having exhaust ports in the wall thereof and a single diameter power piston working in said cylinder, of a charge compressing pump, a single valve between said cylinder and said pump, and a common crank shaft for operating said power piston and said pump, both said power piston and said pump being mounted to simultaneously compress a working charge in said power cylinder.

25. In a two-cycle motor, the combination with an internal combustion cylinder having a single diameter power piston working therein, of a charge compressing pump having a piston working therein, and a single valve between said pump and said cylinder, said pump piston being mounted to compress the working charge and force it directly into said power cylinder during the same period in which said power piston is performing its compression stroke.

26. In an internal combustion engine, a working cylinder having a single diameter power piston working therein, a charge compressing pump operating in conjunction with said working cylinder and having a pump piston in said pump, a common crank shaft connected to said power piston and said pump piston, and a single valve between said working cylinder and said pump, both said power piston and said pump piston being mounted to simultaneously compress a working charge in said cylinder.

In testimony whereof I affix my signature.

JOB HUTCHINSON.
